ELECTRON DISCHARGE DEVICE

Homer G. Anderson, Newtonville, Mass., assignor
to Raytheon Manufacturing Company, Newton,
Mass., a corporation of Delaware

Application January 22, 1947, Serial No. 723,510

7 Claims. (Cl. 250—27.5)

1

This invention relates to electron discharge devices and more particularly to a novel structure for supporting the cathode heating means therein.

The main object of the present invention is to provide means for supporting the cathode heating means without resorting to the use of insulators to accomplish the aforesaid object.

The above and many other objects will become apparent as the illustrative embodiment of the present invention is described and will be readily observable by reference to the accompanying drawing in which:

Fig. 1 is a vertical section through an electron discharge device embodying an illustrative embodiment of the present invention;

Fig. 2 illustrates in greater detail the illustrative embodiment of the present invention;

Fig. 3 presents a vertical section of the lead-in assembly for said electron discharge device; and

Fig. 4 is a view of Fig. 2 taken along line 4—4.

Referring now more particularly to Fig. 1, the reference numeral 10 represents a cylindrical envelope of an electron discharge device of the so-called magnetron type, hermetically sealed at both ends by a pair of caps 11 and 12. Adjacent said caps are the usual pole pieces 11A and 12A associated with this type of electron discharge device. Said envelope and caps may be and preferably are made of copper. Upon the inner surface of said envelope there is provided a central, circular projection 13 to which are attached, as by soldering for example, a plurality of suitably spaced, radially disposed metal plates 14, the inner ends of which constitute anode faces. Said anode faces cooperate with a cathode structure 15 supported substantially centrally of said anode faces, said cathode being preferably of the indirectly-heated, thermionic type.

The cathode 15, see Fig. 2, comprises, in addition to a sleeve 16 of nickel or other conductive material, a screen-like member 17 substantially surrounding said sleeve for the purpose of properly supporting a suitable electron-emissive coating 18 of barium and strontium or other electron-emissive material, and a helically wound electrically insulated heater wire 19. Said heater wire is wound in a manner described in a co-pending application of Homer G. Anderson, Serial No. 562,334, filed November 7, 1944, now Patent No. 2,439,786, dated April 20, 1948. However, in accordance with the present invention, said heater wire is supported within the confines of the conductive sleeve 16, the end 20 of said heater wire being attached, for example, by

2

welding same within and to the lower portion of said conductive sleeve 16.

The opposite end 21 of said heater wire 19 is connected to a lead-in conductor 22 which enters the envelope 10 through a glass seal 23 mounted at the outer end of a conducting pipe 24 which extends through the wall of said envelope 10 and is hermetically secured therein. A second lead-in conductor 25 is sealed through a similar glass seal 23' mounted at the outer end of a second conducting pipe 24'.

Said last-named lead-in conductor 25 is attached, as by welding, intermediate a pair of substantially parallel members 26 and 27, see Fig. 15, one of each of the respective ends thereof terminating in a substantially U-shaped configuration 28 and 29 and extending perpendicularly from said parallel members. The free ends of said U-shaped portions of the parallel members are attached by suitable means to the edge of a substantially circular metal shield member 30, constructed in accordance with the description of aforesaid copending application of Homer G. Anderson. Said shield member is one of a pair 30—31 of such members.

The shield members 30—31 are electrically connected, respectively, by means of metal supports 32 to the inner vertical sides of a pair of dish-like metal members 33—34 attached to and 20 within the opposite ends of said conductive sleeve 16. Both of said last-named members are provided with perforations 35—36, see Fig. 2, in the center thereof. The perforation 36 provides means for egress of the heater wire end 21, sufficient space being provided between the shield member 31 and the dish-like member 34 for the passage of the end 21 of said heater wire to the lead-in conductor 22. Connection of the end of said heater wire to the conductor 22 may be 30 made by fitting a tubular member 37, for example, of platinum, over the heater wire end 21, flattening the opposite end of said tubular member and attaching said flattened portion to the lead-in conductor 22 by welding or other suitable means.

Fig. 2 illustrates more clearly the manner in which said tubular member 37 is attached intermediate the heater wire and the lead-in conductor 22. A tubular member 38, one end of 40 which is terminated in a spade-like formation 39, provides the means for supporting the cathode structure 15 at the upper end thereof, said upper end being so designated with respect to the drawing, by attaching said spade-like portion 39 to the shield member 31. An insulating

sleeve 40, preferably of ceramic material, is disposed within said tubular member 38 and fills substantially the entire length thereof, and surrounds the lead-in conductor 22. One end of said insulating sleeve abuts a shoulder 41 integral with said lead-in conductor. This arrangement serves to center the lead-in conductor 22 with respect to the tubular member 38 and also insulates said lead-in conductor from the heater wire with respect to the end 21 thereof. A glass bead 42, fused around the lead-in conductor 22 and tubular member 38, serves to maintain said tubular member rigidly in place.

Fig. 3 is a cross-sectional view of the lead-in assembly and illustrates the manner in which the reentrant stem 43 maintains the lead-in conductor 22 in coaxial alignment with the conducting pipe 24. Positioned intermediate said reentrant stem 43 and the glass bead 42 is a metal hollow member 44 surrounding the lead-in conductor 22. One end of said hollow member is firmly affixed, as by soldering, to the lead-in conductor to provide a radio-frequency choke, the space between said hollow member 44 and the length thereof being sufficient to perform the aforesaid function. With the exception of the tubular member 38 and its cooperative insulating sleeve 40, together with the particular arrangement provided for connecting said last-named members to the cathode structure 15, the lead-in conductor 25 is similarly supported. A flexible lead 45 is suitably attached to the opposite end of said lead-in conductor 22, and a similar arrangement, not shown, provided for the second-named lead-in conductor 25, to furnish conducting means for any source of heater wire current.

As pointed out previously, Fig. 4 illustrates a view of the shield member 30 taken along line 4-4 of Fig. 2 and shows the particular arrangement for connecting the lead-in conductor 25 to said shield member 30.

The illustrative embodiment of the present invention as above described provides a very simple means for supporting the cathode structure 15 in addition to providing means for conducting heater current to said heater wire 19 without the necessity of utilizing electrical insulating means in the immediate vicinity of said heater wire. This arrangement obviates any possibility of contamination of the cathode by the release of gases from such insulating means due to the proximity thereof to the cathode heating means. Furthermore, the release of gases, for example, such as oxygen, tend to reduce the hardness of the electron discharge device, in this particular embodiment a so-called magnetron. This type of electron discharge device utilizes a very high anode voltage and operates in the microwave spectrum. At such frequencies, the introduction of gases within the envelope 10 tends to alter the dielectric constant therein with a consequent change of the desired frequency in a manner familiar to those versed in this particular art.

A further feature of the present invention makes it possible to utilize thoria coated cathodes. Since this type of coated cathode requires temperatures of the order of 1200° to 1400° centigrade for satisfactory operation, the present invention is adapted to take advantage of the highly electron-emissive properties of thoria coated cathodes.

The embodiment of this invention which has been illustrated and described has been selected

for the purpose of setting forth the principles involved. It will be obvious, however, that the invention may be modified to meet various conditions which may be encountered in different specific uses, and it is, therefore, intended to cover by the appended claims all such modifications which fall within the spirit and scope of this invention.

What is claimed is:

10. An electron discharge device comprising: an envelope containing a cathode and an anode adjacent thereto; a shield member secured to one end of said cathode; heating means within said cathode; a lead-in conductor connected to said heating means; means, carried by said lead-in conductor and attached to said shield member, supporting said cathode; and means, also carried by said lead-in conductor, insulating said lead-in conductor from said supporting means.
15. An electron discharge device comprising: an envelope containing a cathode and an anode adjacent thereto; a shield member secured to one end of said cathode; a heater wire within said cathode; said wire being attached at one end to said cathode, the other end thereof being free; a lead-in conductor connected to the free end of said heater wire; means, carried by said lead-in conductor and attached to said shield member, supporting said cathode; and means insulating said lead-in conductor from said supporting means.
20. An electron discharge device comprising: an envelope containing a cathode and an anode adjacent thereto; shield members secured to the ends of said cathode; heating means within said cathode; a lead-in connected to said heating means; means, carried by said lead-in conductor and attached to one of said shield members, supporting said cathode and means, also carried by said lead-in conductor, insulating said lead-in conductor from said supporting means.
25. An electron discharge device comprising: an envelope containing a cathode and an anode adjacent thereto; shield members secured to the ends of said cathode; heating means within said cathode; said wire being attached at one end to said cathode, the other end thereof being free; a lead-in conductor connected to the free end of said heater wire; means, carried by said lead-in conductor and attached to one of said shield members, supporting said cathode; and means insulating said lead-in conductor from said supporting means.
30. An electron discharge device comprising: an envelope containing a cathode and an anode adjacent thereto; shield members secured to the ends of said cathode; heating means within said cathode; a lead-in connected to said heating means; means, carried by said lead-in conductor and attached to one of said shield members, supporting said cathode and means, also carried by said lead-in conductor, insulating said lead-in conductor from said supporting means.
35. An electron discharge device comprising: an envelope containing a cathode and an anode adjacent thereto; shield members secured to the ends of said cathode; heating means within said cathode; a lead-in connected to said heating means; means, carried by said lead-in conductor and attached to one of said shield members, supporting said cathode and means, also carried by said lead-in conductor, insulating said lead-in conductor from said supporting means.
40. An electron discharge device comprising: an envelope containing a cathode and an anode adjacent thereto; shield members disposed intermediate the respective ends of said cathode and said envelope; electrically conductive means supporting said shield members adjacent the respective ends of said cathode; a heater wire for said cathode, one end thereof being connected to one end of said cathode and the other end thereof being free; a plurality of lead-in conductors, one of said shield members and the other of which is connected to the free end of said heater wire; means, carried by said last-named lead-in conductor and attached to the other of said shield members, supporting said cathode; and means insulating said last-named lead-in conductor from said supporting means.
45. An electron discharge device comprising: an envelope containing a cathode and an anode adjacent thereto; shield members disposed intermediate the respective ends of said cathode and said envelope; electrically conductive means supporting said shield members adjacent the respective ends of said cathode; a heater wire for said cathode, one end thereof being connected to one end of said cathode and the other end thereof being free; a plurality of lead-in conductors, one of said shield members and the other of which is connected to the free end of said heater wire; means, carried by said last-named lead-in conductor and attached to the other of said shield members, supporting said cathode; and means insulating said last-named lead-in conductor from said supporting means.
50. An electron discharge device comprising: an envelope containing a cathode and an anode adjacent thereto; a shield member secured to one end of said cathode; a heater wire disposed within said cathode, one end of said heater wire being connected to one end of said cathode and the balance being electrically insulated from said cathode; a lead-in conductor connected to the free end of said heater wire; means, carried by said lead-in conductor and attached to said shield member, supporting said cathode; and means insulating said lead-in conductor from said supporting means.
55. An electron discharge device comprising: an envelope containing a cathode and an anode adjacent thereto; a shield member secured to one end of said cathode; a heater wire disposed within said cathode, one end of said heater wire being connected to one end of said cathode and the balance being electrically insulated from said cathode; a lead-in conductor connected to the free end of said heater wire; means, carried by said lead-in conductor and attached to said shield member, supporting said cathode; and means insulating said lead-in conductor from said supporting means.
60. An electron discharge device comprising: an envelope containing a cathode and an anode adjacent thereto; a shield member secured to one end of said cathode; a heater wire disposed within said cathode, one end of said heater wire being connected to one end of said cathode and the balance being electrically insulated from said cathode; a lead-in conductor connected to the free end of said heater wire; means, carried by said lead-in conductor and attached to said shield member, supporting said cathode; and means insulating said lead-in conductor from said supporting means.
65. An electron discharge device comprising: an envelope containing a cathode and an anode adjacent thereto; a shield member secured to one end of said cathode; a heater wire disposed within said cathode, one end of said heater wire being connected to one end of said cathode and the balance being electrically insulated from said cathode; a lead-in conductor connected to the free end of said heater wire; means, carried by said lead-in conductor and attached to said shield member, supporting said cathode; and means insulating said lead-in conductor from said supporting means.
70. An electron discharge device comprising: an envelope containing a cathode and an anode adjacent thereto; a shield member secured to one end of said cathode; a heater wire disposed within said cathode, one end of said heater wire being connected to one end of said cathode and the balance being electrically insulated from said cathode; a lead-in conductor connected to the free end of said heater wire; means, carried by said lead-in conductor and attached to said shield member, supporting said cathode; and means insulating said lead-in conductor from said supporting means.
75. An electron discharge device comprising: an envelope containing a cathode and an anode adjacent thereto; a shield member secured to one end of said cathode; a heater wire disposed within said cathode, one end of said heater wire being connected to one end of said cathode and the balance being electrically insulated from said cathode; a lead-in conductor connected to the free end of said heater wire; means, carried by said lead-in conductor and attached to said shield member, supporting said cathode; and means insulating said lead-in conductor from said supporting means.

5 jacent thereto; shield members disposed intermediate the respective ends of said cathode and said envelope; electrically conductive means supporting said shield members adjacent the respective ends of said cathode; a heater wire disposed within said cathode, one end of said heater wire being connected to one end of said cathode and the balance being electrically insulated from said cathode; a plurality of lead-in conductors, one of which is connected to said cathode; means, carried by the second of said lead-in conductors and attached to one of said shield members, for supporting said cathode; and means insulating said last-named lead-in conductor from said supporting means.

7. An electron discharge device comprising: an envelope containing a cathode and an anode adjacent thereto; shield members disposed intermediate the respective ends of said cathode and said envelope; electrically conductive means supporting said shield members adjacent the respective ends of said cathode; a heater wire disposed within said cathode, one end of said heater wire being connected to one end of said cathode and the balance being electrically insulated from said cathode; a plurality of lead-in conductors,

one of which is connected to said cathode; a second of said lead-in conductors being attached to the free end of said heater wire and both being disposed intermediate the opposite ends of said cathode and the shield member adjacent thereto; means, carried by said second-named lead-in conductor and attached to said last-named shield member, for supporting said cathode; and means insulating said lead-in conductor from said supporting means.

Certificate of Correction

Patent No. 2,509,951

May 30, 1950

HOMER G. ANDERSON

It is hereby certified that errors appear in the printed specification of the above numbered patent requiring correction as follows:

Column 4, line 37, after "lead-in" insert *conductor*; line 40, after the word "cathode" insert a semi-colon; line 53, after "one" insert *of which is connected to one*; and that the said Letters Patent should be read with these corrections therein that the same may conform to the record of the case in the Patent Office.

Signed and sealed this 29th day of August, A. D. 1950.
